VENTILATOR PANEL FOR BUILDINGS

Donald H. Ruggles, 2819 S. Sheridan, Tulsa 29, Okla.

Filed Nov. 23, 1964, Ser. No. 82,921

Term of patent 14 years

(Cl. D62—4)

Fig. 1.

Fig. 2.

Fig. 3.

Fig. 4.

Fig. 5. Fig. 7.

Fig. 7.

Fig. 6.

Fig. 8.

FIG. 1 is a perspective view looking upwardly at the outer face of a ventilator for a building as positioned in an upwardly extending wall thereof.

FIG. 2 is an elevational view of the inner face thereof, looking directly at the same.

FIG. 3 is a perspective view of the outer face of a modified form of the ventilator, positioned and viewed as in FIG. 1.

FIG. 4 is an elevational view of the inner face of the ventilator of FIG. 3, viewed as in FIG. 2.

FIG. 5 is a side elevational view of the form shown in FIGS. 1. and 2.

FIG. 6 is a side elevational view of the form shown in FIGS. 3 and 4.

FIG. 7 is a sectional view taken through the louver panel.

FIG. 8 is a fragmentary plan view, on a greatly enlarged scale, looking directly at one of the louver openings and adjacent structure.

This application is a continuation-in-part of my application D. 73,662, filed February 20, 1963, and now abandoned.

I claim:

The ornamental design for a ventilator panel for buildings, as shown and described.
